UNITED STATES PATENT OFFICE.

JOHN W. THOREAU, OF GEDDES, SOUTH DAKOTA.

CHANGEABLE SIGN.

1,314,165.

Specification of Letters Patent. Patented Aug. 26, 1919.

Application filed October 8, 1918. Serial No. 257,368.

To all whom it may concern:

Be it known that I, JOHN W. THOREAU, a citizen of the United States, and a resident of Geddes, in the county of Charles Mix 5 and State of South Dakota, have invented certain new and useful Improvements in Changeable Signs, of which the following is a specification.

My invention relates to improvements in 10 signs and more particularly in changeable signs, and it consists in the constructions, combinations, and arrangements herein described and claimed.

An object of my invention is to provide 15 a sign adapted more particularly for use in show windows, although the use of the sign is by no means limited to this particular field, one of the foremost features being the ability to make innumerable color 20 and display combinations by the use of suitably made insertible letters and devices.

A further object of the invention is to provide a sign of the class described, the 25 tangs or projections of the insertible letters being arranged to provide mutual supports for each other so as to prevent the letter bearing plates from dropping out or becoming disarranged, even should the sign be knocked over.

30 A further object of the invention resides in the novel means for reinforcing or stiffening the card board mount which constitutes the base of the sign.

Other objects and advantages will appear in the following specification, reference being had to the accompanying drawings in which—

Figure 1 is a perspective view of the improved changeable sign,

40 Fig. 2 is a perspective view of the sign, showing how it appears in back,

Fig. 3 is a detail perspective view of a part of Fig. 2, showing how the tangs of the letter bearing plates mutually support 45 each other,

Fig. 4 is a detail cross section on the line 4—4 of Fig. 3,

Fig. 5 is a perspective view of a slightly modified form of sign, wherein stiffening 50 members on the back are used to reinforce the relatively narrow card board mount,

Fig. 6 is a perspective view showing how the letter bearing plates are pressed on the mount, the backwardly turned corners serving to raise the mount and prevent the tangs 55 from striking the table,

Fig. 7 is a perspective view of one of the letter-bearing plates,

Fig. 8 is a perspective view of one of the picture bearing plates,

Fig. 9 is a section similar to Fig. 4, illustrating that the bent tangs may be left straight, and

Fig. 10 is a cross section on the line 10—10 of Fig. 6.

In the simplest form of the invention, the changeable sign comprises a card-board mount 1 in the shape of a flat piece as shown in Fig. 5. A plurality of horizontal rows of slits 2 are made in the card-board mount. 70 In certain forms of the sign as for instance in Fig. 5, a pair of reinforcing ribs or angles 3 are applied to the back to strengthen the card-board mount and prevent it from bending.

75 In another form of the sign, corner pieces 4 and intermediate pieces 5 are bent in for purposes of ornamentation and strengthening the mount, as shown in Figs. 1 and 2. The preferred form of the invention is 80 shown in these two figures, but obviously either form of the invention may be employed at will. This will be governed principally by the shape of the mount. A still further modification consists of leaving off 85 the strengthening ribs 3, and simply using the corner and intermediate pieces 4 and 5 as in Fig. 6.

The sign is primarily intended to be made 90 of card-board or an equivalent substance. For this reason the corner and intermediate pieces 4 and 5 must be strengthened by metal clips 6 which are applied substantially in the manner shown. The same applies to the ribs 3, where metal clips 7 are 95 used for the same purpose. The ribs 3 are made of card-board bent over substantially into the shape shown, and simply glued to the back of the mount.

Either a hanger 8 as in Fig. 5, or a stand 100 9 as in Fig. 2, may be used to support the sign. In the former instance, the ribs 3 form spacers between the wall and the mount 1 to prevent the tangs of the letter bearing plates from pressing against the wall and 105 possibly causing the loosening of the plates.

The stand 9 is pivoted at 10 to strengthening ribs 3 which in the instance in Fig. 2 are arranged along vertical edges of the mount. A lug 11 prevents the stand from 110 swinging too far out. The stand is short enough so as to fall inside of the lower

strengthening rib 3 when it is desired to lay the sign on a table for the insertion of the tangs of the letter bearing plates as illustrated in Fig. 6.

- 5 The letter bearing plates 12 have tangs 13 which are to be pressed into the slits 2. In applying the plates as in spelling a word, companion tangs of companion plates are pressed into the same slit. The friction between the two is sufficient to hold the plates on the mount even should the sign be inadvertently turned over in the show window. It is an existing defect in signs of this nature, that immediately upon slightly 10 tilting the sign, the letters jumble up and even fall out. The construction in Figs. 4 and 9 positively prevents such an occurrence.

In order to insure the retention of the plates 12, the tangs 13 are slightly bent as 20 at 13^a in Fig. 4. In applying the plates, the tips 13^b of companion tangs engage as shown and exert a pressure both at the point of contact 13^c and against the walls of the slit 2. It has been found by experience however, that the straight tangs 13 in Fig. 9 accomplish practically the same purpose.

The natural rough nature of the card-board in the cut slits 2, serves to amply hold the plates in place when two tangs are crowded into the same slit. It is to be observed in a number of the views, especially Figs. 7 and 8, that the tangs 13 are inclined downwardly to further aid them in staying in place.

35 A distinctly novel feature of this sign resides in the use of a picture plate 14. This plate is provided with two or more and preferably four, tangs 13 by means of which the plate is securely fastened on 40 the mount.

In setting up a sign of this kind, special emphasis is laid on the fact that the letter plates 12 adjoin each other and that no spaces are left between them. This has an 45 important advantage. The ground of a certain series of letter plates is to be made of a desired color. Card-board mounts with grounds of various colors are also to be made. By the use of the two, pleasing and 50 attractive color combinations can be designed and the effect is heightened by the continuous base of the applied letter plates. Here the advantage of the elimination of spaces between the plates becomes apparent.

55 While the construction and arrangement of the changeable sign is that of a generally

preferred form, obviously modifications and changes may be made without departing from the spirit of the invention or the scope of the claims.

60 I claim:—

1. A sign, comprising a mount with suitably arranged slits, letter plates, and tangs carried by the letter plates, adjacent tangs of companion letter plates being inserted 65 into a single slit, to hold the letter plates in place by the mutual binding of one tang on the other, said tangs including means formed thereon for increasing the tension between them.

70 2. A sign, comprising a mount with symmetrically arranged vertical slits, letter plates applicable to the mount, each having a pair of tangs, companion tangs of companion plates being insertible into a single slit to frictionally bind on each other and against the edges of the slit, and means embodied in the mount for holding it raised from the table to prevent the tangs from striking the table upon insertion.

75 3. A sign, comprising a card-board mount with horizontal rows of slits, letter plates applicable to the mount, each having a pair of tangs with outwardly bent portions, companion tangs of companion plates being insertible into the same slit, the extreme edges of the bent portions engaging and causing the exertion of a pressure between the plates and against the walls of the slit; means on the back of the mount reinforcing it and 80 acting as a spacer when laid on a table, said means including rearwardly directed strengthening members carried by the mount; a stand pivoted in certain ones of 85 said members and arranged to fall within the lower one of said members when closed, and a lug for limiting the outward movement of the stand.

90 4. A sign, comprising a mount with a ground of any desired color having a plurality of symmetrically arranged vertical slits, and letter plates with grounds of contrasting colors, provided with tangs, adjacent tangs of companion plates being insertible in the same slit and arranged to 95 frictionally bind on each other and exert tension laterally against the edges of the slit when inserted, and provide an unbroken contrasting letter plate ground.

100 JOHN W. THOREAU.
